UNITED STATES PATENT OFFICE.

ANDREW A. KRAMER AND ALVAH M. GRIFFIN, OF KANSAS CITY, MISSOURI.

VALVE-OPERATING-MECHANISM TANK.

Application filed September 19, 1923. Serial No. 663,654.

To all whom it may concern:

Be it known that we, ANDREW A. KRAMER and ALVAH M. GRIFFIN, citizens of the United States, residing at Kansas City, 5 in the county of Jackson and State of Missouri, have invented certain new and useful Improvements in Valve-Operating-Mechanism Tanks; and we do declare the following to be a full, clear, and exact description of the invention, such as will enable others skilled in the art to which it appertains to make and use the same, reference being had to the accompanying drawings, and to the figures of reference marked 10 thereon, which form a part of this specification.

This invention relates to dispensing tanks and particularly to a compartmental dispensing tank forming part of a tank wagon 20 construction. The primary object of the invention is to provide means for shutting off the flow of flammable material such as oil in the case of fire.

The tanks of tank wagons are usually 25 divided into compartments, each compartment containing a different grade or quality of oil and from each compartment there extends a pipe discharging at the rear end adjacent to the can box. The ports in the 30 compartments communicating with the pipes are normally closed by valves which may be unseated when the door of the can box is opened so that oil may flow into the pipes. When the door of the can box 35 is closed, the valves are permitted to seat. Our invention contemplates means for causing the valves to close in the case of fire when the door of the can box is open, whether by automatically or manually 40 controlled means and the invention consists of certain novel parts and combinations of parts all of which will be specifically described hereinafter, reference being had to the accompanying drawings, in which—

45 Fig. 1 is a perspective view of a tank equipped with our invention, part of the tank wall being broken away.

50 Fig. 2 is a detailed perspective view of a release latch for manually releasing the valves to closing position.

Fig. 3 is a detailed perspective view of one of the valve stem cams.

Fig. 4 is a fragmentary perspective view of the tank showing the valve rod release.

Fig. 5 is a detailed perspective view of 55 one of the valves.

Fig. 6 is a detailed perspective view of the release latch bolt.

Fig. 7 is a fragmentary perspective view of a tank showing a modified form of a 60 valve bar release, and

Fig. 8 is an end view of the tank with the modified form of release applied.

The tank 1 may be suitably supported upon a vehicle body and it may have at 65 one end the usual cab 2, and the can box 3, the can box having a closure or door 4. Each compartment is provided at its bottom with an opening, communicating with the pipe 5 and in each opening is a valve 70 cage 6 having a threaded portion 7 engaging the opening. The valve cage 6 is provided with a guiding column in which is a slidably secured valve stem 9 on the lower end of which is a valve 10 to cover and 75 uncover the opening 11 through which the oil passes on its way to the pipes 5, it being understood of course that the pipes 5 have dispensing nozzles 12 of appropriate construction. The valve stem 9 extends 80 through a gland 13 on the cam bracket 14, the cam bracket carries a cam 15 on the edge of which a rocker arm 16 may move. The rocker arm or crank 16 is rigid with the valve stem 9 so that when the arm 16 85 rides on the high lobe of the cam the valve 10 will be unseated, but when it is permitted to ride down on to the low lobe of the cam the valve 10 will be seated. The arms 16 are all connected to a cam rod or 90 bar 17 received between the bifurcated portion 18 of a pivoted lever 19. The pivoted lever 19 carries a pivoted arm 20, having an offset tooth 21 constituting a stop for the spring press bolt 22 slidable in the 95 barrel 23 and adapted to engage the end 24 of the lever 19 so that when the latch is in full line position (Fig. 2) the lever 19 and the arm 20 will be rocked together to form a rigid connection between the rod 17 100 and the rod 25 connected to the elbow lever 26 pivoted at 27 to the tank and connected to the rigid arm 28 on door 4 by a fusible link connection 29. When the door 4 is

opened the rod 25 will be moved longitudinally toward the rear end of the vehicle. The rod 17 will be moved in a forward direction through the levers 19 and 20 which are now rigidly connected one to the other through the latch bolt 22. Therefore when the door 4 is opened the arms 16 will ride up the cams 15 to unseat the valve 10 and permit oil to flow into the pipes so it can be drawn off through any of the dispensing nozzles 12. When the door is closed the reverse action takes place and the valves 10 will seat.

If fire occurs while the door 4 is opened and the valves are unseated, the fusing of the link 29 will ordinarily break the connection between arm 28 and arm 26 so that the valve arms 16 can ride down the cams and close the valves 10 shutting off the supply of oil from the pipes. Sometimes the link does not fuse, or fire may occur away from the link, or for some other reason the device does not automatically operate, then the connection between the levers 19 and 20 will be broken by pulling the cord 30 on the end of the latch bolt 22, disengaging the levers 19 and 20 and permitting the valves to close. The cord or cable 30 is accessible from a point adjacent to the cab or at the front of the tank, this location being desirable because the latch bolt 22 will have to be manually actuated and of course it is desired to place the manual control as far away from the flame as practical.

In Fig. 7 we have shown a slightly modified form of connection between the door and the rod 25. In Figs. 7 and 8 the door 31 is a vertical swinging door as distinct from a transversely swinging door and the door 31 carries an upstanding rod 32 having an arm 33 connected to a fusible link 34, similar to the link 29. In other respects the construction will be substantially that of the preferred form. It will be apparent from the foregoing that means has been provided for controlling the supply lines from the several compartments of the tank in case of fire and that means may be either manually or automatically controlled so that in case

of fire the closing of the valves to the supply pipe will be insured.

What we claim and desire to secure by Letters-Patent is:—

1. In combination with a tank having a discharge opening therein, a valve normally closing said opening and a can box on the tank having a door, of mechanism connecting the valve and the door whereby the opening movement of the door will unseat the valve, the mechanism having a fusible link as a part thereof.

2. In combination with a tank having a discharge opening therein, a valve normally closing said opening and a can box on the tank having a door, of mechanism connecting the valve and the door whereby the opening movement of the door will unseat the valve, the mechanism having a fusible link as a part thereof near one end of the tank and an independent manually operated valve releasing means at the other.

3. In a valve controlling mechanism having compartmental oil tanks, a plurality of vertical stems having valves on the lower ends for closing openings in the compartments by gravity, cams adjacent to the stems, lever arms on the stems to ride over the cams, a bar connecting said lever arms, a rod substantially parallel with the bar and a release lever normally connecting the rod and bar.

4. In a valve controlling mechanism having compartmental oil tanks, a plurality of vertical stems having valves on the lower ends for closing openings in the compartments by gravity, cams adjacent to the stems, lever arms on the stems to ride over the cams, a bar connecting said lever arms, a rod substantially parallel with the bar and a release lever normally connecting the rod and bar, said release lever consisting of two members and a release latch for normally holding the two members rigid.

In testimony whereof we affix our signatures.

ANDREW A. KRAMER.
ALVAH M. GRIFFIN.
